Harry Schrodé ATTORNEY.

UNITED STATES PATENT OFFICE

HENRY GERKIN, OF OAKLAND, CALIFORNIA

HAIR WAVING APPLIANCE

Application filed November 14, 1932. Serial No. 642,583.

This invention is a hair waving appliance to be used for the purpose of providing a permanent wave.

Waving devices which at present are obtainable, bring the heat in direct contact with the hair and are usually made in the form of a core on which the hair is wrapped or wound, the heating element being clamped about the hair on the core.

My invention contemplates the heating of the hair from a remote point, that is, by having the heating unit spaced from the core and the hair, and in such manner as to obviate the possibility of the hair coming in contact with any part of the heating unit, the heating being done principally by the heating of the air surrounding the hair.

The main object of the invention therefore is to provide a hair waving appliance in which the heating unit is not brought into contact with the hair and in which the heating is accomplished by the heating of the air about the hair by means of a heating unit remotely located.

Another object of the invention is to provide an appliance as outlined with a housing forming a dead air space in which a heating unit is disposed and which is adapted to heat the air within the housing, the air in turn heating the hair.

A further object of the invention is to interpose a heat insulating material between the core and the heating unit so as to prevent any possibility of the hair coming into direct contact with the heating unit.

A still further object of the invention is to provide the device with an insertable heating unit and a removable core, so that the hair can be wound about the core, the core placed within the housing, and the housing closed, after which the core can be tightened as may be desired and the heating unit inserted.

Other objects and advantages of the invention will become apparent as the following description is read on the drawing forming a part of this specification, and in which similar reference characters are used to designate similar parts throughout the several views, of which:

Fig. 1 is a plan view of the invention with the top cover open.

Fig. 2 is a front elevation of the invention.

Fig. 3 is an end elevation.

Fig. 4 is a section taken on line 4—4 of 55 Fig. 2.

The invention consists of a housing comprising a bottom 10, rear wall 11 and end walls 12 and 13, the end wall 13 having a slot 14 formed from the top and terminating in an arcuate recess to form one quarter of the bearing, the front edge of the end wall 13 continuing perpendicular to the axis of the recess as indicated at 15. The wall 12 terminates at its forward edge in a pintle sleeve 16. The rear wall 11 is provided with ears 17 to which is hingedly attached as indicated at 18 a cover 19, the forward edge of this cover having integral spring clips 20 which extend downwardly at right angles relative to the top surface of the cover 19.

The front door 21 is hinged to the end 12 as indicated at 22 to permit swinging the door outwardly from the housing, the other end of this door terminating in an end element 23 which forms the remaining portion of the end 13, this portion 23 having a complementary recess 24 to form another quarter of the bearing, the cover 19 having a downwardly projecting portion 25 which is 80 provided with a semi-circular recess, completing the bearing for this end. Indents or other suitable means 26 is provided for retaining the cover 19 in closed position, the cover 19 through the resilient elements 20 85 coincidently retaining the front cover 21 in closed position.

Removably mounted within the housing as shown at 22 is a partition formed of heat insulating material, this member having apertures 27 and 28 formed respectively adjacent the bottom and the top thereof, this partition dividing the housing into two compartments, one of the compartments being provided for the reception of the heating unit 29, and the other compartment being provided for reception of the core 30.

The front door 21 has an inwardly projecting closure member 31 at the bottom, the bottom 10 of the housing terminating at a point 100

below the core 30, and the member 31 terminating at a point spaced from the edge of the bottom 10, forming a slot for reception of the strand of hair 32.

5. An aperture is provided in the end 12 for reception of the pivot 33 which is integral with the core 34, the other end of the core terminating in a pivot 35, this pivot being rotatable in the bearing formed by the elements 13, 23, and 25, and frictionally held by the member 25 when the cover 19 is closed, the pivot 35 terminating in a non-circular projection 36 for cooperation with a suitable key.
15. A suitable aperture is also provided in the end 13 for insertion of the element 29, this element being provided with suitable terminals 37 and 38 for connection to a source of electric power.
20. The operation of the device is as follows:

The top cover is swung to open position as shown in Fig. 1 and the front cover 21 is swung outwardly on the hinge 16—22 releasing the core 34 which is removed by withdrawal from the aperture in the end 12.

30. A strand of hair is wound about the core 34, the core is re-inserted in the housing, the front door 21 is then closed, and the top door 19 is closed over the front door locking the top door and coincidentally locking the front door and frictionally securing the pivot 35 in its bearing.

35. The heating element 29 is then inserted in the aperture provided therefor in end 13 and connected in circuit and allowed to remain in circuit for a predetermined length of time. The circulation through the apertures 27—28 and from the heating unit compartment to the core compartment, heats the hair without direct contact of the heating unit, thereby providing more satisfactory heating of the hair and producing exceptional results.

40. Removal of the hair after the waving operation merely requires the opening of the top cover 19 and the front cover 21 and removal of the core 34.

45. It will be understood that the housing may be formed of heat insulating material, such as compressed asbestos or the housing may be made of sheet metal and covered with suitable heat insulating material.

50. Having described an operative device it will be understood that variations in construction and arrangement of parts which are consistent with the appended claims may be resorted to without detracting from the spirit or scope of the invention or sacrificing any of the advantages thereof.

I claim:

60. 1. A hair waving appliance, in combination, a core on which the hair is wound, a housing for the core and a heating unit insertible in said housing and remotely located relative to the core whereby the hair on the core is indirectly heated, said housing having a

dividing wall for dividing the housing into a heating unit compartment and a core compartment.

2. A hair waving appliance, in combination, a core on which the hair is wound, a housing for the core and a heating unit insertible in said housing and remotely located relative to the core whereby the hair on the core is indirectly heated, said core being removably and rotatably mounted and frictionally retained in adjusted position, said housing having a dividing wall for dividing the housing into a heating unit compartment and a core compartment.

3. A hair waving appliance comprising a housing, a core removably mounted in said housing, a heating unit insertible in said housing and a dividing wall between the heating unit and the core.

4. A hair waving appliance comprising a housing, a core removably mounted in said housing, a heating unit insertible in said housing and a dividing wall between the heating unit and the core, said housing having a top cover and a front cover, closing of the top cover coincidentally securing the top cover and the front cover.

5. A hair waving appliance comprising a housing, a core removably mounted in said housing, a heating unit insertible in said housing and a dividing wall between the heating unit and the core, said housing having a top cover and a front cover, closing of the top cover coincidentally securing the top cover and the front cover, and coincidentally forming a bearing for the core pivot and frictionally securing the core.

6. A hair waving appliance comprising a housing, a core removably mounted in said housing, a heating unit insertible in said housing and a dividing wall between the heating unit and the core, said housing having a top cover and a front cover, closing of the top cover coincidentally securing the top cover and the front cover, said dividing wall having openings therethrough to permit circulation of the heat by means of the air within the housing.

7. A hair waving appliance comprising a housing, a core removably mounted in said housing, a heating unit insertible in said housing and a dividing wall between the heating unit and the core, said housing having a top cover and a front cover, closing of the top cover coincidentally securing the top cover and the front cover, and coincidentally forming a bearing for the core pivot and frictionally securing the core, said dividing wall having openings therethrough to permit circulation of the heat by means of the air within the housing.

8. A hair waving appliance comprising a housing, a core removably mounted in said housing, a heating unit insertible in said housing and a dividing wall between the heat-

ing unit and the core, said housing having integral bottom, back and ends, a hinged cover for the top and a hinged door for the front, said cover and said door being secured in 5 closed position by closing of the cover.

9. A hair waving appliance comprising a housing, a core removably mounted in said housing, a heating unit insertible in said housing and a dividing wall between the 10 heating unit and the core, said housing having integral bottom, back and ends, a hinged cover for the top and a hinged door for the front, said cover and said door being secured in closed position by closing of the cover, one 15 of said ends terminating in spaced relation to the front and having a recess forming a portion of a bearing for said core, said door having the remainder of the end integral therewith and having a complementary recess 20 forming another portion of the bearing whereby convenient removal of the core is provided.

10. A hair waving appliance comprising a housing, a core removably mounted in said 25 housing, a heating unit insertible in said housing and a dividing wall between the heating unit and the core, said housing having integral bottom, back and ends, a hinged cover for the top and a hinged door for the 30 front, said cover and said door being secured in closed position by closing of the cover, said hinged cover having a depending portion having an arcuate recess formed in the 35 bottom edge frictionally cooperating with the core pivot and coincidentally forming a portion of the bearing therefor, said depending portion being received in a recess formed in one end of the housing.

11. A hair waving appliance comprising a 40 housing, a core removably mounted in said housing, a heating unit insertible in said housing and a dividing wall between the heating unit and the core, said housing having integral bottom, back and ends, a hinged 45 cover for the top and a hinged door for the front, said cover and said door being secured in closed position by closing of the cover, one of said ends terminating in spaced relation to the front and having a recess forming 50 a portion of a bearing for said core, said door having the remainder of the end integral therewith and having a complementary recess forming another portion of the bearing whereby convenient removal of the core is provided, said hinged cover having a depending 55 portion having an arcuate recess formed in the bottom edge frictionally cooperating with the core pivot and coincidentally forming a portion of the bearing therefor, said depending portion being received in a recess formed in one end of the housing.

12. A hair waving appliance comprising a housing, a core removably mounted in said 60 housing, a heating unit insertible in said housing and a dividing wall between the heat- 65

ing unit and the core, said housing having integral bottom, back and ends, a hinged cover for the top and a hinged door for the front, said cover and said door being secured in closed position by closing of the cover, 70 the bottom terminating in spaced relation to the front of the housing, said hinged door having a bottom portion projecting rearwardly and terminating in spaced relation to the front edge of the bottom of the housing 75 forming a slot for passage of the hair therethrough.

13. A hair waving appliance comprising a housing, a core removably mounted in said housing, a heating unit insertible in said housing and a dividing wall between the heating unit and the core, said housing having integral bottom, back and ends, a hinged cover for the top and a hinged door for the front, said cover and said door being secured in closed position by closing of the cover, 80 the bottom terminating in spaced relation to the front of the housing, said hinged door having a bottom portion projecting rearwardly and terminating in spaced relation to the front edge of the bottom of the housing 85 forming a slot for passage of the hair therethrough, one of said ends terminating in spaced relation to the front and having a recess forming a portion of a bearing for said 90 core, said door having the remainder of the end integral therewith and having a complementary recess forming another portion of the bearing whereby convenient removal 95 of the core is provided.

14. A hair waving appliance comprising a housing, a core removably mounted in said housing, a heating unit insertible in said housing and a dividing wall between the heating unit and the core, said housing having integral bottom, back and ends, a hinged cover for the top and a hinged door for the front, said cover and said door being secured in closed position by closing of the cover, the 100 bottom terminating in spaced relation to the front of the housing, said hinged door having a bottom portion projecting rearwardly and terminating in spaced relation to the front edge of the bottom of the housing forming a slot for passage of the hair therethrough, said hinged cover having a depending portion having an arcuate recess formed in the bottom edge frictionally cooperating with the core pivot and coincidentally forming a portion of the bearing therefor, said depending portion being received in a recess formed in one end of the housing.

15. A hair waving appliance comprising a housing, a core removably mounted in said housing, a heating unit insertible in said housing and a dividing wall between the heating unit and the core, said housing having integral bottom, back and ends, a hinged cover for the top and a hinged door for the front, said cover and said door being secured 125 130

in closed position by closing of the cover, the bottom terminating in spaced relation to the front of the housing, said hinged door having a bottom portion projecting rearwardly and terminating in spaced relation to the front edge of the bottom of the housing forming a slot for passage of the hair therethrough, one of said ends terminating in spaced relation to the front and having a recess forming a portion of a bearing for said core, said door having the remainder of the end integral therewith and having a complementary recess forming another portion of the bearing whereby convenient removal of the core is provided, said hinged cover having a depending portion having an arcuate recess formed in the bottom edge frictionally cooperating with the core pivot and coincidentally forming a portion of the bearing therefor, said depending portion being received in a recess formed in one end of the housing.

16. A hair waving appliance comprising a housing, a core removably mounted in said housing, a heating unit insertible in said housing and a dividing wall between the heating unit and the core, said dividing wall having openings therethrough to permit circulation of the heat by means of the air within the housing, said housing having integral bottom, back and ends, a hinged cover for the top and a hinged door for the front, said cover and said door being secured in closed position by closing of the cover.

17. A hair waving appliance comprising a housing, a core removably mounted in said housing, a heating unit insertible in said housing and a dividing wall between the heating unit and the core, said dividing wall having openings therethrough to permit circulation of the heat by means of the air within the housing, said housing having integral bottom, back and ends, a hinged cover for the top and a hinged door for the front, said cover and said door being secured in closed position by closing of the cover, one of said ends terminating in spaced relation to the front and having a recess forming a portion of a bearing for said core, said door having the remainder of the end integral therewith and having a complementary recess forming another portion of the bearing whereby convenient removal of the core is provided, said hinged cover having a depending portion having an arcuate recess formed in the bottom edge frictionally cooperating with the core pivot and coincidentally forming a portion of the bearing therefor, said depending portion being received in a recess formed in one end of the housing.

18. A hair waving appliance comprising a housing, a core removably mounted in said housing, a heating unit insertible in said housing and a dividing wall between the heating unit and the core, said dividing wall hav-

ing openings therethrough to permit circulation of the heat by means of the air within the housing, said housing having integral bottom, back and ends, a hinged cover for the top and a hinged door for the front, said cover and said door being secured in closed position by closing of the cover, one of said ends terminating in spaced relation to the front and having a recess forming a portion of a bearing for said core, said door having the remainder of the end integral therewith and having a complementary recess forming another portion of the bearing whereby convenient removal of the core is provided, said hinged cover having a depending portion having an arcuate recess formed in the bottom edge frictionally cooperating with the core pivot and coincidentally forming a portion of the bearing therefor, said depending portion being received in a recess formed in one end of the housing, the bottom terminating in spaced relation to the front of the housing, said hinged door having a bottom portion projecting rearwardly and terminating in spaced relation to the front edge of the bottom of the housing forming a slot for passage of the hair therethrough.

In testimony whereof I affix my signature.
HENRY GERKIN.
